NILS D. LEVIN, OF COLUMBUS, OHIO, ASSIGNOR TO THE JEFFREY MANUFACTURING COMPANY, OF COLUMBUS, OHIO, A CORPORATION OF OHIO.

CUTTING CHAIN.

Application filed June 4, 1920. Serial No. 386,479.

To all whom it may concern:

Be it known that I, NILS D. LEVIN, a citizen of the United States, residing at Columbus, in the county of Franklin and State of Ohio, have invented certain new and useful Improvements in Cutting Chains, of which the following is a specification, reference being had therein to the accompanying drawing.

10 The present invention relates to certain new and useful improvements in cutting chains for coal mining and other machines.

The especial object of this invention is to provide a chain of strong and simple construction comprising means for securely holding the renewable cutter bits during operation of the machine which will permit of expeditious and convenient replacement and adjustment of said bits.

20 The means by which I attain this object are fully set forth in the following specification and illustrated in the accompanying drawings of which

Fig. 1 is a side elevation of a portion of 25 a chain embodying my invention.

Fig. 2 is a plan view partly in section of one of the links shown in Fig. 1.

Fig. 3 is a longitudinal sectional view taken along the line III—III of Fig. 2.

30 Fig. 4 is a transverse sectional view taken along the line IV—IV of Fig. 1 showing the relation of the chain parts to the guide members of a mining machine cutter arm of well known construction.

35 Like numerals refer to similar parts in the several figures.

In the mining of coal, as commonly practiced, kerfs are cut in the coal body to permit a sufficient distortion of the material adjacent said kerfs to dislodge fragments for transportation from the mine. The machines most commonly used for the formation of said kerfs are provided with cutting tools removably attached to suitable chains by the movement of which said tools are forced into the coal to cut it. Tools so used become dull, requiring renewals which occasion interruption of the operation of the machine, at more or less frequent intervals depending upon the character of the material being mined. I am aware that many devices have been proposed for attaching the cutter bits to mining machine chains which, while securely holding them in correct position dur-

ing operation, will permit their quick and easy replacement and adjustment. However all such devices with which I am familiar possess certain inherent defects which it is the object of the present invention to overcome.

In the drawings I have illustrated a mining machine chain comprising a series of block links 1 connected by strap links 2 and pintles 3. The chain thus formed is adapted to slide upon the edge of the cutter bar 4 between the side plates 5 which are provided with hardened steel renewable guide bars 6. Formed on each of the links 1 and 2 are laterally extending flanges 7 which engage the inner edges of the guide bar 6 to prevent accidental displacement of the chain. Formed on each of the block links 1 is an upwardly projecting extension 8 having an aperture 9 in which is slidably mounted a renewable cutter bit 10. The bit 10 is formed with a straight shank 11 of such shape and proportions as to form a snug sliding fit with the sides of the aperture 9. Formed in the extension 8, and extending longitudinally forward from the aperture 9, is a slot 12 in which is mounted a locking cam 13. The cam 13 is rotatable about a transverse pivot pin 14 and is so formed that when rotated to cause its rearward side to move inwardly of the chain it will engage the bit shank 11 and press it against the rearward surface of the aperture 9 to frictionally grip the bit 10 against movement relative to the block link 1. Formed on the cam 13 are two oppositely disposed faces 15 and 16 adapted to be struck by an inward blow of a hammer, or other suitable tool, to cause the rotation of the cam about its pivot pin 14. When the cutter bit 10 has been placed in the desired position of adjustment the cam 13 may be rotated into contact with the shank 11 and, by a light stroke of a suitable hammer upon the face 15, driven into forcible engagement therewith to produce a wedging action which securely grips the bit shank against movement relative to the block link 1. The form and location of the cam 13 cause it to co-operate with the tendency to downward movement of the bit thereby increasing its gripping effect as the working pressure upon the bit increases. When it is desired to remove or adjust the bit 10 a light stroke of the hammer upon the

surface 16 is sufficient to rotate the cam in the bit releasing direction and permit free movement of the bit longitudinally of the aperture 9.

5. When a cutter chain is associated with the cutter bar of a mining machine, as illustrated in Fig. 4, the guide plates 5 completely enclose the chain parts with the exception of the extensions 8 and the devices 10 mounted thereon. As part of the cutter bar is overhung by the frame of the mining machine a large part of the chain is so inaccessible that, as heretofore constructed, adjustment may be effected over only a part of 15 its length, requiring repeated movements of the chain during the process of its renewal or adjustment. In my improved cutter chain the oppositely disposed faces 15 and 16 make possible the rotation of the cam 13 in either 20 direction by the inward movement of a hammer or other suitable tool, thereby permitting convenient adjustment of the chain in substantially all positions of its path of travel. This increased facility with which 25 the bits may be adjusted in all positions of the chain greatly increases the efficiency of operation of the mining machine.

What I claim is:

1. In a chain of the class described, the 30 combination with a block link, an aperture in the block, a cutter tool having a shank longitudinally slidable in said aperture, and a rotatable cam adapted to engage said shank to clamp said tool in any preferred position 35 of adjustment.
2. In a chain of the class described, the combination with a block link, an aperture in the block, a cutter tool having a shank longitudinally adjustable in said aperture, 40 and a rotatable cam mounted forwardly of said aperture and adapted to engage said shank to lock said tool in adjusted position.
3. In a chain of the class described, the combination with a block link, an aperture in the block, a cutter tool having a shank longitudinally slidable in said aperture, a cam 45 mounted in said block at the forward side of said aperture to contact therewith and so shaped that the normal working pressure upon the bit tends to rotate the cam in a direction to lock said bit in adjusted position.
4. In a chain of the class described, the combination with a block link, an aperture 55 in the block, a cutter tool having a shank longitudinally slidable in said aperture, and a rotatable member adapted to frictionally

engage said shank to hold said tool in adjusted position.

5. In a chain of the class described, the 60 combination with a block link, an aperture in the block, a cutter tool having a shank longitudinally slidable in said aperture, and a rotatable member mounted forwardly of said aperture and adapted to frictionally engage 65 said shank to hold said tool in adjusted position.

6. In a chain of the class described, the combination with a block link, an aperture in the block, a cutter tool having a shank longitudinally slidable in said aperture, and a rotatable member mounted in said block at the forward side of said aperture to frictionally engage 70 said shank and so shaped that the normal working pressure upon said 75 bit tends to increase the frictional resistance to movement of said tools relative to said links.

7. In a chain of the class described, the combination with a block link, an aperture in 80 the block, a cutter tool having a shank longitudinally slidable in said aperture, a rotatable cam adapted to be forced into engagement with said shank to clamp said tool in adjusted position, and means to rotate 85 said cam.

8. In a chain of the class described, the combination with a block link, an aperture in the block, a cutter tool having a shank longitudinally slidable in said aperture, a 90 rotatable cam adapted to engage said shank, and oppositely disposed faces formed on said cam and adapted to be struck to cause rotation of said cam.

9. In a tool holder of the class described, 95 the combination with a body, an aperture in said body, a tool having a shank longitudinally slidable in said aperture, a rotatable grip mounted on said body adjacent said aperture and so disposed that pressure on 100 said tool inwardly of said aperture tends to tighten said grip upon said shank.

10. In a tool holder of the class described, the combination with a body, an aperture in said body, a tool having a shank longitudinally 105 slid able in said aperture, a gripping member mounted on said body adjacent said aperture and so disposed that pressure on said tool inwardly of said aperture tends to tighten said grip upon said shank.

In testimony whereof, I affix my signature.

NILS D. LEVIN.
